UNITED STATES PATENT OFFICE.

JOHN J. STROBOT, OF CHICAGO, ILLINOIS, ASSIGNOR TO FIDELITY BRASS MANUFACTURING COMPANY, OF CHICAGO, ILLINOIS, A CORPORATION OF ILLINOIS.

CUTTING-TORCH.

1,281,871.

Specification of Letters Patent. Patented Oct. 15, 1918.

Application filed July 10, 1918. Serial No. 244,211.

To all whom it may concern:

Be it known that I, JOHN J. STROBOT, a citizen of the United States of America, and resident of Chicago, Illinois, have invented a 5 certain new and useful Improvement in Cutting-Torches, of which the following is a specification.

This invention relates to cutting torches of that kind in which oxygen and acetylene gas 10 are mixed in suitable proportions to produce a hot flame for cutting steel or other metal.

Generally stated, the object of the invention is to provide a novel and improved construction of the nozzle and head of the torch, 15 for the purpose of more effectively combining the acetylene gas with the oxygen, and to prevent flashing back of the flame within the nozzle and head, thereby to insure greater safety in the handling of the torch.

It is also an object to provide certain details and features of construction and combinations tending to increase the general efficiency and desirability of a cutting torch of this particular character.

To these and other useful ends the invention consists in matters hereinafter set forth and claimed and shown in the accompanying drawings, in which—

Figure 1 is a longitudinal section of the 30 head of the cutting torch embodying the principles of the invention showing the inner nozzle in side elevation.

Fig. 2 is a side elevation of said inner nozzle separated from the other parts of the 35 head.

Fig. 3 is an end view of said inner nozzle. Fig. 4 is a section on line 4—4 in Fig. 1.

As thus illustrated, the head of the torch comprises a casting 1 having a boss 2 into 40 which high pressure tube 3 is screwed, and a boss 4 into which the acetylene tube 5 is screwed, or both of these tubes can be brazed in place if desired. The casting 1 contains a bore having a mixing chamber 6 which is 45 open at its lower end, being disposed vertically and slightly inclined relatively to the horizontal tubes. The upper portion 7 of this bore 6 is somewhat reduced and threaded and is connected by a passage 8 with the end of the tube 3 to receive the high pressure oxygen. The boss 4 contains a bore 9 which connects the bore 6 with the tube 5, and the inner tube 10, which carries the so-called pre-heating oxygen, extends through the 50 tube 5 and through the bore 9 to a point where it is flush with the side of the bore 6, it being understood that sufficient space is provided between the inner surface of the tube 5 and the outer surface of the tube 10 for the passage of the acetylene gas. The 60 inner nozzle has a threaded portion 11 which is screwed into the reduced threaded bore portion 7, and has a cylindrical portion 12 which extends downward in the bore 6, the latter being of greater diameter than said cylindrical portion. At a point below the bottom of the casting 1 the inner nozzle is provided with a short hexagonal portion 13, and below the latter with a downwardly and gradually tapered portion 14 which terminates at its lower end in a flange 15, this inner nozzle being made of brass or other suitable metal. Also, said inner nozzle has a short reduced portion 16 below the flange 15 and an enlarged lower end portion 17 which 65 is slightly tapered in a downward direction. The outer nozzle has a hexagonal upper end portion 18 which is screwed upon the externally threaded boss or lower end portion 19 of the casting 1, and the lower end portion 20 of this outer nozzle fits the tapered end portion 17 of the inner nozzle. Internally, it will be seen the outer nozzle 70 has a bore 21 which incloses the tapered portion 14 and the lower portion of the hexagonal portion 13, and also the flange 15 of the inner nozzle. This bore 21 is straight and terminates, preferably, at its lower end in a shoulder 22 which is slightly below the upper end portion 17 of the inner nozzle. The 75 upper end of this bore 21 terminates in a bevel 23, and an enlarged distributing chamber 24 is formed immediately above this bevel, below the lower end portion 19 of the casting 1 previously described. The 80 flange 15 has its annular edge disposed a distance from the sides of the bore 21, and the inner nozzle thus formed, has a central longitudinal bore or passage 25 for the high pressure oxygen. The portion 17 is provided with a plurality of longitudinally disposed passages 26, which communicate at their upper ends with the space just below the flange 15, and which are open at their 85 lower ends to discharge the mixture of acetylene gas and oxygen which passes from the tubes 5 and 10 into the bore or mixing chamber 6, then into the distributing chamber 24, and then into the bore 21, in a manner that 90 will be readily understood. Preferably, 95 100 105 110

these passages 26 converge slightly in a downward direction so that the jets of acetylene gas and oxygen will meet or come together at a point some distance from the end 5 of the nozzle, and will combine with the jet of high pressure oxygen discharged from the passage 25 when the torch is in operation.

The acetylene gas and oxygen entering 10 the bore 6 are thoroughly mixed before they pass around the flange 15 to enter the upper ends of the passages 26, and it will be seen that the passage 27 in the end portion 28 of the tube 10 extends close to the side 15 of the cylindrical portion 12 of the inner nozzle, and that the bore 9 is of greater diameter than this end portion 28 of the inner tube, so that the acetylene gas is discharged into the bore 6 before it encounters 20 the oxygen supplied through the tube 10, whereby the initial mixing occurs in the bore 6 around the inner nozzle. Also, the flange 15 is disposed immediately above the upper ends of the passages 26 and extends 25 sufficiently close to the inner surface of the bore 21 to prevent flashing back of the flame within the bore 21, so that this danger is considerably reduced. The hexagonal portion 13 fits the upper end of the bore 21, or 30 very nearly so, as may be desired, so that a plurality (six in this case) of parallel passages are provided to connect the chamber 24 with the space surrounding the reduced tapered portion 14, whereby the mixture 35 of oxygen and acetylene gas is more or less divided while passing from the chamber 24 into the bore 21, this arrangement tending to insure the desired results, not only with regard to the proper mixing and supply 40 of the oxygen and acetylene gas to the passages 26, but also with respect to the desirability of having the torch head so constructed that flashing back of the flame within the nozzle will be less liable to occur, 45 so that the torch will be safer to handle. In addition, the hexagonal portion 13 is adapted to receive a wrench for the purpose of screwing the inner nozzle into the head or casting, and for the purpose of removing 50 the inner nozzle when such is necessary or desirable.

What I claim as my invention is:—

1. In a torch, an outer nozzle, an inner nozzle inclosed by the outer nozzle, and a head to which said nozzles are removably connected, said inner nozzle having an enlarged end portion provided with passages, and having a flange disposed in position to extend over the inner ends of said passages.

2. A structure as specified in claim 1, said inner nozzle having a downwardly tapered portion immediately above said flange, a polygonal portion immediately above said 65 tapered portion, and a cylindrical portion

immediately above said polygonal portion, said head and outer nozzle providing space around said tapered and polygonal and cylindrical portions of the inner nozzle.

3. A structure as specified in claim 1, 70 said enlarged end portion of the inner nozzle being slightly tapered, and the outer nozzle being internally tapered to fit said tapered portion of the inner nozzle.

4. In a torch, an inner nozzle and an outer 75 nozzle, and a head to which said nozzles are removably connected, said inner nozzle having an enlarged end portion provided with longitudinally extending passages, and having a polygonal portion connected by a 80 downwardly tapered portion to said end portion of the inner nozzle, said tapered portion being longer than said polygonal portion, and the inner nozzle having a cylindrical portion above said polygonal portion, with a longitudinal passage extending 85 through the inner nozzle from end to end thereof.

5. A structure as specified in claim 4, said outer nozzle having a straight bore of uniform diameter which incloses said tapered portion and which terminates at its lower end in a shoulder slightly below the upper end of said enlarged lower end portion of the inner nozzle.

6. A structure as specified in claim 1, 90 said outer nozzle having a straight bore which extends downward to a point below said flange.

7. In a torch, a head having an upper 100 tube connected thereto for high pressure oxygen, a lower tube connected thereto for acetylene gas, and an inner oxygen tube within said lower tube, said head having a downwardly extending bore forming a mixing chamber, and having a horizontally disposed bore extending from the end of said lower tube to said chamber, said inner tube extending through said bore and also terminating at said chamber.

8. In a cutting torch, an inner nozzle and an outer nozzle, the inner nozzle having a tapered outer end portion to tightly fit the end of the outer nozzle, a polygonal middle portion which is entirely within the outer 115 nozzle, a reduced portion connecting the tapered portion with the polygonal portion, a reduced inner end portion which extends into the outer nozzle to joint the polygonal portion and which is threaded to screw into 120 the torch, a longitudinal bore extending from one end of said inner nozzle to the other end thereof, and a plurality of converging passages in said tapered portion, said inner nozzle having a flange disposed 125 close above the upper ends of said converging passages.

9. In a cutting torch, a head having a plurality of inlet passages, an inner nozzle screwed into said head, an outer nozzle 130

screw-connected with said head and formed with an upper bore and a lower bore to inclose the inner nozzle, and supply means connected with said inlet passages, said inner nozzle having a central bore communicating with one of said passages, said head providing a mixing chamber extending around the inner nozzle and communicating with one of said passages, with a distributing chamber in the upper end of said outer nozzle to receive the gas from said mixing chamber, said inner nozzle having an intermediate polygonal portion fitting said upper bore, and a tapered end portion inclosed by the lower bore and provided with converging outlet passages, with a reduced portion between the polygonal portion and the tapered portion, said polygonal portion providing a plurality of parallel passages leading from said distributing chamber to said cavity, and the end portion of said outer nozzle being formed below said lower bore to receive the tapered end portion of the inner nozzle to form a tight joint between the ends of the two nozzles, so that the discharge from said converging passages is concentrated in the discharge from said inner nozzle, said reduced portion of the inner nozzle being tapered downward and having a flange disposed close above the upper ends of said converging passages.

Signed by me at Chicago, Illinois, this 22d day of June, 1918.

JOHN J. STROBOT.
